PACKER

Joseph O. Brumby, Los Angeles, Calif., assignor
to R. E. Kline

Application October 12, 1938, Serial No. 234,612

3 Claims. (CL 166—1.2)

This invention relates to improvements in well packers, and particularly to that class of well packers known as bypass packers wherein there is a passage through the packer permitting the flow of fluid therethrough as the packer is lowered into the well, the passage being closed when the packer is seated.

An object of the invention is to provide a very simple form of packer construction having a minimum number of parts which are of such design as to produce a very sturdy durable structure. In packers of this general character there is usually a slip cone carrying slips with a packing means above the slip cone and casing-engaging springs which hold the slips against vertical movement while the slip cone is being lowered relatively thereto to seat the slips. When the slips have been set the mandrel of the packer carrying a valve is lowered onto a valve seat which closes the bypass through the packer and at the same time compresses and thus expands the packing.

Heretofore, a bayonet joint has been used as a means for holding the casing-engaging springs in lowermost position with respect to the mandrel while the device was being lowered into the well. The bayonet joint type of construction is disadvantageous for several reasons including the constant danger of inadvertently breaking or shearing off the pin. It is also disadvantageous in that, on recovering the packer from the well, it is necessary to return the pin of the bayonet joint to its initial position otherwise the casing-engaging springs are capable of setting the slips at any time that the recovering string of pipe is lowered, such as when the recovering string of pipe is being lowered onto the slips on the rotary table.

It is an object of the present invention to provide a superior construction for holding the casing-engaging springs in lowermost position with respect to the mandrel while the device is being lowered into the well and which will release the casing-engaging springs from the mandrel upon rotation of the lowering string of pipe. Thereafter, on recovering the packer from the well on merely pulling up the mandrel by the recovering string of pipe, the casing-engaging springs will be automatically reconnected to the mandrel and held in lowermost position without involving rotation as in the case of a bayonet joint.

An important feature of the present invention is on the construction of the type of releasable connection that is located between the mandrel and the casing-engaging springs, which is advan-

tageous over the previously used bayonet joint or J slot type of connection in that it does not afford as easy an opportunity for sand to settle between the parts and interfere with their operation as in the case of the bayonet joint.

With the foregoing and other objects in view, which will be made manifest in the following detailed description and specifically pointed out in the appended claims, reference is had to the accompanying drawings for an illustrative embodiment of the invention, wherein:

Fig. 1 is a view in side elevation of the improved well packer illustrating it in that position during which it is lowered into or recovered from a well;

Fig. 2 is a longitudinal vertical section through the packer in the same position shown in Fig. 1;

Fig. 3 is a view similar to Fig. 2 showing the packer in that position wherein the slips have been set and the packing means is about to be compressed and thus expanded;

Fig. 4 is a partial view in vertical section illustrating the packing means as having been expanded;

Fig. 5 is a horizontal section taken substantially upon the line 5—5 of Fig. 2; and

Fig. 6 is a horizontal section taken substantially upon the line 6—6 of Fig. 2.

Referring to the accompanying drawings wherein similar reference characters designate similar parts throughout, the improved packer comprises a tubular or hollow mandrel 10 having an external shoulder 11 formed thereon and at its bottom an enlargement 12. At the upper end of the mandrel there is provided a head 13 which constitutes a valve presenting a tapered valve surface 14. This head is preferably threaded onto the mandrel and locked in place as by set screw 15. It may be externally kerfed as at 16 to facilitate engagement by an overshot should occasion require. The head is preferably internally threaded as at 18 for attachment to a drill pipe or other lowering or recovering string of pipe. Around the upper end of the mandrel there is disposed a sleeve 19 which is spaced from the mandrel providing a passage 20 thereabout. This sleeve has its upper end externally flanged as at 21 to retain a collar 22 that forms a valve seat 23 on which the head 13 is designed to seat. Below the collar 22 there is disposed packing 24. This packing is preferably in the form of a rubber sleeve reinforced with fabric indicated at 24a. The fabric is embedded in the rubber and has additional thicknesses adjacent the top and bottom as shown at 24b. This additional reinforcement 25

near the top and bottom causes the ends of the packing to have less tendency to become wedged between the body of the packer and the casing. The exterior of the sleeve may be equipped with 5 reinforcing fabric as indicated at 24c and preferably has a plurality of circumferential grooves indicated at 25. The packing is supported around the sleeve on a suitable bushing 26 threaded onto the lower end of the sleeve 19. The bushing 26 is, in turn, threaded into the upper end of a slip cone 27. The slip cone has external downwardly converging slip ways 28 for slips 29. The slips and slip ways are preferably dovetailed in cross section as shown on Fig. 6. The inner 10 faces of the slips are preferably grooved as at 30 and set screws 31 are driven into the slip cone with their heads disposed in the grooves 30. Engagement between the heads of the set screws 31 and the upper ends of the grooves 30 limits upward movement of the slip cone with respect to the slips when the slips are held in their lowermost positions, thus preventing engagement between the head 13 and seating surface 23 during lowering into the well.

25 As clearly shown in Fig. 5, the slip cone has inwardly extending internal vertical ribs 32 which fit relatively closely around the mandrel 10 above shoulder 11. Between these ribs are 15 passages 33 which, in conjunction with the passage 30 within sleeve 19 and the passage within the collar 22, permit fluid to flow upwardly through the slip cone and through the packing means and the valve seat thereon while the tool is being lowered into the well. Downward movement of the slip cone relative to mandrel 10 is 20 limited by the bottoms of these ribs 32 engaging shoulder 11. Slip reins 34 are pivotally connected to the bottoms of the slips and to a rein collar 35 which is mounted on the upper end of 25 a sleeve 36 fitting about the lower end of the mandrel. This rein collar may be locked in place when threaded onto the sleeve 36 by means of set screws 37. On the lower end of sleeve 36 there is mounted a collar 38 to which the lower ends of 30 bowed casing-engaging springs 39 are connected. The upper ends of the casing-engaging springs are connected to a collar 40 which is slideable on sleeve 36. The lower portion of collar 38 is in the nature of a hollow truncated cone, as indicated at 41, and this cone is divided into a plurality of downwardly extending segments 42 by means of upwardly extending splits 43. The enlargement 12 is externally threaded with an upwardly tapering thread and provides a shoulder 45 44 engageable by the lower ends of the extensions 42. This shoulder is preferably downwardly and inwardly inclined and the lower ends of the extensions 42 are shaped complementary thereto to resist any tendency of the extensions 50 to be spread when forced against the shoulder. The extensions 42 are stiff but at the same time yieldable and are internally threaded as at 45 with threads complementary to the tapered threads on enlargement 12.

65 The operation and advantages of the improved well packer are as follows: When it is desired to set the packer within a casing C the packer is connected to a lowering string of pipe such as a drill pipe (not shown). It is lowered into the 70 well in that position shown in Figs. 1 and 2 wherein the split nut formed by the extensions or fingers 42 is in engagement with the threads on enlargement 12. When these parts are in engagement the casing-engaging springs 39 and 75 the sleeve 36 are locked in their lowermost posi-

tions with respect to the mandrel 10. Consequently, the slips 29 are held in their lowermost or contracted positions with respect to the slip cone 27. During the lowering of the packer into the well in this position, fluid encountered in the well may readily flow up through the passages 33 in the slip cone through the passage 28 between the mandrel and sleeve 19 and through the collar 22. In this position it will be noted that the head 13 is held in open or unseating position 10 with respect to the valve seat 23.

When the packer has reached the desired level in the well the drill pipe or other lowering string of pipe is rotated, rotating the mandrel and thus unscrewing the enlargement 12 from within the 15 split nut formed by the extensions or fingers 42. It will be appreciated that this nut will be held against rotation by the springs 39 engaging the casing C. These springs serve a double function, namely to hold the split nut stationary during the unscrewing of enlargement 12 and also as a means for holding sleeve 36 against relative movement with respect to the casing while the mandrel lowers the slip cone 27. When the split nut is released from enlargement 12, the lowering string of pipe and the mandrel are lowered, thus lowering the slip cone 27 with respect to the slips 29 which are held by the casing-engaging springs 39. The slip cone is lowered into the slips and expanded thereby into engagement with the casing. The tool then occupies a position substantially as that illustrated in Fig. 3.

When the slips have been set the lowering string of pipe and mandrel are lowered still farther so as to impose some of the weight on collar 22. At the same time the seating surface 14 will firmly engage the valve seat 23, thus closing the bypass through the packer. The weight imposed on the collar forces the collar to telescope downwardly on sleeve 19 and to compress and thus expand the packing rings into engagement with the interior surface of the casing C, thus, in effect, isolating the upper portion of the well from the lower portion of the well except through the interior of mandrel 10. It will be noted that the sleeve 19 is rigid or stationary with respect to the slip cone and that the collar 22 telescopes on the sleeve to compress the packing. The upper, inner corner of the sleeve is beveled off, consequently when valve 13 is seated on the collar no cuttings or debris in the bypass passage through the packer will interfere with the expansion of the packing rings. In most prior forms of packers sleeve 19 is attached to collar 22 and is forced downwardly through the packing rings when the valve is seated. There is usually a shoulder spaced from the bottom of the sleeve formed on the interior of the slip cone. This shoulder is apt to collect debris or cuttings, and when such cuttings collect on the shoulder they interfere with the sleeve being forced downwardly and thus prevent proper expansion of the packing rings. By the present arrangement danger of cuttings interfering with the expansion of the packing rings is effectively overcome.

When it is desired to recover the packer from the well it is merely necessary to lift the lowering string of pipe. This lifts the mandrel and lifts the head 13 off of collar 22. On pulling the enlargement 12 upwardly into engagement with the split nut, the fingers or extensions 42 merely spring outwardly permitting the threaded exterior of the enlargement to enter and to have its threads engage the internal threads on these extensions. It will be noted that in this oper-

ation of re-establishing the connection between the casing-engaging springs 39 and the mandrel that it is not necessary to rotate the mandrel. Instead, the enlargement merely snaps into the 5 split nut and is then held in this position. Upward movement of the mandrel of course lifts the slip cone 27 causing the slips 29 to be drawn into contracted position. The packer may thus be pulled from the well and any fluid above the 10 packer may drain through its bypass. It will be noted that upward pull on the mandrel causes the ends of the extensions 42 to firmly engage the inclined shoulder 44 so that even upon severe upward strains the shape of the inclined shoulder 15 is such that it will not tend to spread or expand the extensions 42. By the use of a tapered thread on the mandrel the friction springs 39 need only be strong enough to hold the extensions 42 while they are snapping over approximately one thread, 20 yet when the extensions are snapped over a distance of about one thread all of the threads are in firm engagement.

It should be noted that whenever the enlargement 12 and the split nut are in engagement that 25 it is necessary to unscrew the enlargement 12 from the split nut in order to accomplish a release. However, these parts may be reconnected merely by lifting the mandrel with respect to the split nut and that no rotation is required.

30 The shoulder 44 on the enlargement 12 forms a very sturdy base for supporting sleeve 36 and the casing-engaging springs 39 on the mandrel. The construction is such that there is no danger of any parts becoming broken during operation 35 in the well, such as for example the shearing off of the pin of a bayonet joint.

In the present construction the reins 34, the slips 29, and the set screws 31 serve to hold the slip cone 27 in its lowermost position when the 40 enlargement 12 and the split nut are in engagement. With this form of construction it is not necessary to employ any independent means for holding the slip cone, the packing means, and the collar 22 down and out of engagement with 45 the seating surface 14 while the device is being lowered into the well.

From the above-described construction it will be appreciated that a novel, simple, and durable packer is provided which is of extremely simple 50 operation and which will assure proper recovery of the packer from the well, permitting fluid to readily flow therethrough both during the lowering and recovering operations but effectively packing off the well when seated.

Various changes may be made in the details of 55 construction without departing from the spirit or scope of the invention as defined by the appended claims.

I claim:

60 1. A well packer comprising a mandrel, a slip cone mounted on the mandrel, packing means

supported on the slip cone, means providing a valve seat on the packing means by which the packing means may be compressed and thus laterally expanded, there being provision for flow up through the slip cone, packing means, and valve seat, a valve on the mandrel adapted to seat on the valve seat, slips on the slip cone, slip holding means for holding the slips against vertical movement with respect to the slip cone when the slip cone is lowered by the mandrel, and means for 10 holding the slip holding means against vertical movement with respect to the mandrel while the device is being lowered into a well, comprising means providing an upwardly tapered thread on the mandrel, and means providing a resilient split 15 nut on the slip holding means engageable therewith.

2. A well packer comprising a mandrel, a slip cone mounted on the mandrel, packing means supported on the slip cone, means providing a 20 valve seat on the packing means by which the packing means may be compressed and thus laterally expanded, there being provision for flow up through the slip cone, packing means, and valve seat, a valve on the mandrel adapted to 25 seat on the valve seat, slips on the slip cone, slip holding means for holding the slips against vertical movement with respect to the slip cone when the slip cone is lowered by the mandrel, and means for holding the slip holding means against 30 vertical movement with respect to the mandrel while the device is being lowered into a well comprising means providing an upwardly tapered thread on the mandrel, means providing yieldable fingers on the slip holding means, the inner 35 faces of which are threaded for threaded engagement with the tapered thread on the mandrel, and a shoulder at the base of the tapered thread engageable by the lower ends of the fingers. 40

3. A well packer comprising a mandrel, a slip cone mounted on the mandrel, packing means supported on the slip cone, means providing a valve seat on the packing means by which the packing means may be compressed and thus laterally expanded, there being provision for flow up through the slip cone, packing means, and valve seat, a valve on the mandrel adapted to seat on the valve seat, slips on the slip cone, and slip holding means for holding the slips against vertical movement with respect to the slip cone when the slip cone is lowered by the mandrel including an upwardly tapered thread on the mandrel, there being a downwardly and inwardly inclined shoulder at the base of the tapered thread, means providing yieldable fingers, the inner faces of 50 which are threaded for threaded engagement with the tapered thread and the ends of which are engageable with the shoulder, said yieldable fingers being connected to the slips. 55

J. O. BRUMBLY. 60
